DISPLAY PACKAGE

Stanley Ward Burnham, Elizabeth, N. J., assignor
to Merck & Co., Inc., Rahway, N. J., a corpora-
tion of New Jersey

Application March 15, 1934, Serial No. 715,607

5 Claims. (Cl. 206—78)

This invention relates to certain new and useful improvements in display packages.

The primary object of the invention is to provide a display package for medicinal tablets, pills, capsules and other articles of manufacture with the articles confined within a wrapper or folder comprising a body portion or bottom having a hinged cover with window openings in the cover permitting visual inspection of the article within the display package while the cover is in closed position.

While it is intended that this display package may contain various articles of manufacture, such articles for purposes of clarity will herein be referred to as medicinal tablets. It is known that tablets have been wrapped in regenerated cellulose containers and it is also known to provide a "string" of tablets contained in a regenerated cellulose tube with the walls of the tube caused to adhere at spaced points to provide pockets for the tablets with the tube severable at the wall connected points for the dispensing of a single tablet.

An object of this invention is to confine the tablets or the like in regenerated cellulose wrappers with the display package for the regenerated cellulose wrapped tablets comprising a body portion having a depressed channel therein receiving the regenerated cellulose wrapped tablets and a hinged cover for the body portion having an elongated window opening therein overlying the depressed channel in the body portion for the display of the tablets and also to provide clearance for the upwardly projecting portion of the tablet to permit the cover to be quite tightly closed upon the body portion.

It is a further object of the invention to provide a display package of the foregoing character wherein the regenerated cellulose wrapped tablets are arranged in pairs, the regenerated cellulose wrapper being closed at its ends and having an intermediate contacting portion providing two compartments while the display package has a pair of spaced longitudinally extending depressed channels for the respective reception of the tablets with the intermediate portion of the regenerated cellulose wrapper adhesively or otherwise secured to the intermediate portion of the body portion, the intermediate portion of the regenerated cellulose wrapper being weakened to facilitate tearing while the hinged cover for the body portion has a pair of window openings respectively overlying the depressed channel.

With the above and other objects in view that

will become apparent as the nature of the invention is better understood, the same consists in the novel form, combination and arrangement of parts hereinafter more fully described, shown in the accompanying drawing and claimed.

5

In the drawing:

Figure 1 is a top plan view of a display package constructed in accordance with the present invention, showing the window openings in the cover of the package for the display of the regenerated cellulose wrapped tablet contents;

Figure 2 is an end elevational view of the display package;

Figure 3 is a perspective view of a pair of regenerated cellulose wrapped tablets showing the weakened intermediate portion of the wrapper and the connected intermediate and end portions of the wrapper;

Figure 4 is a plan view of the display package in open position exposing the regenerated cellulose wrapped tablet contents;

Figure 5 is a plan view of the display package in open position with the contents removed to illustrate the depressed channels in the body portion and the window openings in the hinged cover; and

Figure 6 is a cross-sectional view taken on line 6—6 of Figure 2.

The display package as shown more clearly in Figs. 4 and 5 and designated in general by the reference character 10 is illustrated as of rectangular form, although the same may assume any shape desired and includes a body portion 11 having a pair of spaced longitudinally extending depressed pockets or channels 12 spaced from the ends of the body portion and providing an intermediate wall 13 and outer border walls 14. The cover 15 is connected to the body portion 11 by means of a flexible hinge 16 and said cover has a pair of spaced longitudinally extending window openings 17 of the same dimensions as the pockets 12 that register with the pockets when the cover is in closed position as illustrated in Figs. 1 and 6. The window openings 17 are separated by an intermediate wall 18 and outer lateral walls 19 that respectively overlie the walls 13 and 14 of the body portion 11 when the cover is in closed position as shown in Figure 6.

The tablets 20 are preferably arranged in pairs and are contained in regenerated cellulose wrapper or tube, the regenerated cellulose tube having the end portions 21 and the intermediate portion 22 moved into contact and adhesively or otherwise retained to provide spaced compartments 23 to contain the tablets 20. As shown in

45

50

55

55

detail in Fig. 3, the intermediate portion 22 of the regenerated cellulose tube is slotted as at 24 inwardly from opposite side edges to provide a weakened tearing line.

- 5 The regenerated cellulose tubes carrying the tablets are assembled in the display package by having the intermediate portions 22 overlying the intermediate wall 13, separating the depressed pockets 12 and adhesively or otherwise retained in engagement with the intermediate wall 13, the compartments 23 respectively extending into the depressed pockets 12 while the outer end portions 21 of the regenerated cellulose tube overlie the outer lateral walls 14 of the body portion as shown in Figs. 4 and 6. The tablets 20 are of a size when placed in the depressed pockets 12 to project upwardly above the upper plane of the body portion 11 and extend upwardly into the window openings 17 of the cover 15 when the latter is 10 in closed position as shown in Figs. 1 and 6. The contents of the package are readily displayed through the window openings 17 as shown in Figure 1, and of course, the outer face of the cover 15 may carry any suitable advertising information 15 desired. To remove a tablet from the display package, the cover 15 is first opened and the thumb nail of one hand may be engaged with the weakened slotted tearing line 24 of the regenerated cellulose tube and either compartment 23 of the tube readily removed from the package 20 by pulling force sufficient to overcome the adhesive retention of the tube in the package.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed.

I claim:—

1. A display package, comprising a body portion having a pair of spaced longitudinally extending pockets therein defining an intermediate wall, a hinged cover having a pair of window openings to respectively overlie the pockets and a plurality of regenerated cellulose tubes having the ends and intermediate portions contacting to provide a pair of article containing compartments with the compartments respectively seated in the pockets and with the intermediate portions of the tubes anchored to the intermediate wall.
- 45 2. In a display package, comprising a body portion having a pair of spaced longitudinally ex-

tending pockets therein defining an intermediate wall, a hinged cover having a pair of window openings to respectively overlie the pockets and a plurality of regenerated cellulose tubes having the ends and intermediate portions contacting to provide a pair of article containing compartments with the compartments respectively seated in the pockets and with the intermediate portions of the tubes anchored to the intermediate wall, and said pockets extending upwardly into the window 10 openings.

3. A display package, comprising a body portion having a pair of spaced longitudinally extending pockets therein defining an intermediate wall, a hinged cover having a pair of window openings to respectively overlie the pockets and a plurality of regenerated cellulose tubes having the ends and intermediate portions contacting to provide a pair of article containing compartments with the compartments respectively seated in the 15 pockets and with the intermediate portions of the tubes anchored to the intermediate wall, the intermediate portions of the tubes having weakened tearing lines to facilitate removal of a compartment from the pocket and package.

4. A display package, comprising a body portion having a pair of spaced longitudinally extending pockets therein defining an intermediate wall, a hinged cover having a pair of window openings to respectively overlie the pockets and a 20 plurality of regenerated cellulose tubes having the ends and intermediate portions contacting to provide a pair of article containing compartments with the compartments respectively seated in the pockets and with the intermediate portions of the tubes anchored to the intermediate wall, the intermediate portions of the tubes having weakened tearing lines to facilitate removal of a compartment from the pocket and 25 package.

5. A display package comprising a body portion having longitudinally extending pockets therein defining intermediate walls between such pockets, a hinged cover having a pair of window 30 openings to respectively overlie the pockets, and a plurality of regenerated cellulose tubes having the ends and intermediate portions contacting to provide a plurality of article-containing compartments with the compartments respectively seated 35 in the pockets, and with the intermediate portions of the tubes anchored to the intermediate walls.

STANLEY WARD BURNHAM.
